8 Claims. (Cl. 250—41.9)

1

This invention is concerned with mass spectrometry and has particularly to do with the ion collection system of a mass spectrometer. The invention adapts the spectrometer in which it is incorporated to be used both for mixture analysis with automatic attenuation and isotope ratio analysis, the changeover being carried out without physically disturbing the collection system.

The principal of mass spectrometry is in general one of ionizing a sample to be analyzed, as by an electron beam, segregating ions in accordance with their mass-to-charge ratio by inducing spatial separation thereof, and selectively discharging as at a collector electrode, ions of a given mass-to-charge ratio. The current developed by discharge of a group or beam of ions of the same mass-to-charge ratio is proportional to the partial pressure of the particles in the original sample from which these particular ions were derived. Hence, a method is afforded for calculating the concentration of these particles or their parent molecules in the sample.

In analyzing a sample for more than one component, the segregated ion beams constituting a part or all of the mass spectrum of the particular sample are successively focused on the collector electrode so that a plurality of separate discharge currents are obtained, each being proportional to the number of ions in a particular beam. The mass spectrum is scanned in this fashion by varying one or more of the parameters affecting the spatial separation of the ions of differing mass-to-charge ratio. In some instances electric scanning is preferred, in which case propelling potentials are varied to effectuate sweep of the ion beams across a so-called "resolving slit" giving access to the collector electrode. In other instances magnetic scanning is preferred, in which case the transverse magnetic field established across the spectrometer is varied in intensity to bring about the same sweep of the ion beams across the resolving slit.

The currents produced by ion discharge are generally converted to proportional voltages across a dropping resistor, the voltages are amplified, and the amplified signals are recorded on either a multichannel recorder such as an oscillograph or on a single channel such as a pen and ink recorder. The recorded signals appear as separate peaks on the record with each peak representing ions of a different given mass-to-charge ratio, the recorded trace returning to "zero" or base level between succeeding peaks. The peak heights are determined by the amplifier-recorder sensitivity as well as by the number of ions of a

2

given mass-to-charge ratio represented by the given peak.

Because of the wide differences in the number of ions which may be encountered in different beams as a result of large concentration spreads in the original sample, it is necessary when using a single channel recorder to provide means for varying the sensitivity of the recorder so as to adapt it to this wide variation in ion abundance. If such provision is not made, the less abundant ions of a given spectrum will not develop a peak of sufficient height on a record having a full scale sensitivity such as to accommodate the most abundant ions. This principle has been recognized in the prior art and various so-called anticipator circuits have been suggested for anticipating the ion abundance in succeeding beams of the spectrum and suitably adjusting the sensitivity of the recorder in advance of each separate peak.

In general these anticipator circuits employ a double collector or target system. The two ion targets are so arranged that a so-called auxiliary or anticipator target receives the full ion current signal in advance of the collector target, the resolution of the instrument being such that the auxiliary or anticipator target senses on a particular ion beam before this beam strikes the collector target. The anticipator signal is amplified and fed to a calculating device which selects the optimum attenuation range to be used in recording the data when the same ion beam is focused on the main collector. The information as to the proper attenuation range is delivered from the calculator to the main recording channel at a pre-selected time intermediate the recording of succeeding peaks. Such anticipator or attenuating circuits are described in my co-pending applications Serial No. 82,337, filed March 19, 1949, and Serial No. 132,691, filed September 1, 1950.

Mass spectrometers have also been adapted to measurement of isotope ratios again by inclusion of a pair of collector electrodes. In this application one of the two electrodes is referred to as a low current electrode and at this electrode the ion beam derived from molecules of a low abundance isotope is discharged. The other electrode is referred to as the high current electrode and the ion beam of the more abundant isotope is focused and discharged at this electrode. In the majority of instances the less abundant isotopes are of higher mass and hence the low current or main target electrode must lie on a larger radius than the high current electrode irrespective of direction of beam sweep in the instrument. For ex-

ample, consider the analysis of carbon dioxide to determine the relative abundance of the C¹³ and C¹² isotopes. C¹² being the most abundant isotope, the CO₂⁴⁴ ions will be focused on the high current or auxiliary collector and the CO₂⁴⁵ ions will be focused on the low current or main collector.

In isotope ratio analysis it is generally desired to measure the ratio of the ion currents rather than the absolute concentrations of the components. Accordingly, the amplification and recording circuit connected to the two collector electrodes is frequently arranged as a null balance network wherein the current developed at one collector is effectively divided by the other to give a recorded value representative of the indicated ratio. A network of this character is illustrated and described in some detail in U. S. Patent 2,456,426 issued to Alfred O. C. Nier on December 14, 1948, and in co-pending application Serial No. 104,030, filed by Robert L. Sink on July 11, 1949.

Either in automatic attenuation or isotope ratio application a mass spectrometer with a main target or collecting electrode and an auxiliary electrode is required with each electrode being connected to separate amplification means. However, the same two electrodes are not adaptable both to attenuated mixture analysis and isotope measurement for the reasons (1) different resolution is required in each instance, and (2) for most efficient operation the auxiliary electrode should be on opposite sides of the main collector in the two circumstances, interchangeability of function between the main electrode and the auxiliary electrode being impossible because of the problem of resolving power.

For automatic attenuation the resolution required is that necessary to distinguish between adjacent masses at the upper end of the mass range bearing in mind that spatial separation of ion beams of one mass unit difference is inversely proportional to the mass. This requirement insures that only a single ion beam will fully strike either collector electrode at a given time. For isotope ratio measurements the ideal resolving power is that which will resolve adjacent masses only at the lowest extremity of the expectable mass range. A higher degree of resolution would preclude measurement of hydrogen-deuterium ratios for example. Hence a dual collector system for isotope ratio measurements is not satisfactory for automatic attenuation application. This lack of interchangeability is totally independent of any differences in external circuitry required for the two operations, it being otherwise a relatively simple matter to interconnect the two collector amplifiers to alternately develop a voltage ratio or to vary recorder sensitivity responsive to the output of one of the amplifiers.

As to the orientation of the auxiliary collector in each instance, this problem is affected by the general practice of scanning spectra from low mass to high mass. This practice is dictated by two considerations. One of these is the relatively more rapid depletion of low mass components of a sample because of the molecular flow characteristics of the system and the other is the difficulty of arriving at the proper initial accelerating voltages to focus the highest mass of a given sample when that mass is not known. Both of these factors therefore, dictate the practice of scanning from low mass to high mass. For this reason the anticipator or auxiliary tar-

get must be located at a greater distance from the center of curvature than the main collector for automatic attenuation and at a lesser distance for isotope measurement, bearing in mind that the greater the mass the larger the radius of curvature at a given accelerating voltage and that the most abundant isotope of a given element is generally that of lowest mass or more specifically of lower mass than the rare isotope which is of interest.

At the present time the conversion of a mass spectrometer from one mode of operation to the other, i. e. from mixture analysis with automatic attenuation to isotope ratio analysis, is impractical in requiring removal of one collector system and replacement of another for the several reasons given above. When the whole collector system has to be thus replaced to change the mode of operation, the vacuum system must be broken down and then re-established. Such a process is sufficiently costly in both time and money to be substantially prohibitive on a periodic basis.

I have now developed a collection system which is suitable for both types of operation and which is adapted to be connected to associated amplification and recording channels of the types described in the aforementioned co-pending applications for carrying on either type of analysis. My invention contemplates in a mass spectrometer having an ion source, an analyzer chamber, means for propelling ions from the ion source through the analyzer chamber and for sorting the ions in the analyzer chamber. The combination comprising a barrier electrode and first, second and third collector electrodes arranged in successively spaced relationship adjacent the outlet end of the analyzer chamber, the barrier electrode having an aperture there-in forming a first resolving slit, the first collector electrode having a narrower aperture in off-center alignment with the barrier aperture and forming a second resolving slit, the second collector electrode being positioned to mask a portion of the aperture in the first collector and forming therewith a third effective resolving slit, the third collector electrode being positioned to receive ions passing through this third resolving slit, and amplification means for amplifying the ion discharge signals at the several collector electrodes.

The feature which makes the present invention possible is the independent determination of the resolving power of the instrument with respect to isotope ratio and automatic attenuation application. The first collector electrode, above referred to, is connected to the auxiliary amplifier for mixture analysis, the resolving power being determined by the dimensions of the barrier aperture and the extent to which the aperture is masked by this electrode. The second collector electrode is connected in this circumstance at a reference potential substantially equal to that of the first and third collector electrodes acting as a shield. For isotope ratio measurements the reverse connection of the first and second collector electrodes is employed and resolution in this instance is a function of the size of the second resolving slit formed by the aperture in the first collector electrode and the extent to which this aperture is masked by the second collector. As a consequence, the resolving power of the mass spectrometer may be predetermined and may be in-

dependently set depending upon the use to which the spectrometer is to be put.

The invention will be more clearly understood by reference to the accompanying drawing which shows diagrammatically a conventional 180° mass spectrometer provided with a collection system in accordance with the invention.

Referring to the drawing, the mass spectrometer there shown comprises an ion source 10, analyzer chamber 12 and a collector system 14, all enclosed within an envelope 16. The envelope may be evacuated through a conduit 18 connected to evacuating means (not shown). Communicating apertures 19 between the analyzer chamber and envelope enable evacuation of the analyzer chamber and ion source through the envelope. In some instruments the envelope 16 is omitted by making the tube 12 vacuum tight and by extending it to enclose the collection system.

The ion source is provided with an inlet conduit 20 for receiving a sample of gas to be analyzed, the gas being ionized in the ion source by an electron beam 22 developed at a source not shown. The ions are propelled from the ionization chamber under the influence of a potential established between a pusher electrode 24, a first accelerating electrode 25 and a terminal accelerating electrode 26, the last two electrodes being apertured to pass and collimate the ion beam. Under the influence of this potential established between the electrodes and the source of ion formation, ions are propelled from the point of formation at the electron beam as a thin heterogeneous ribbon or beam B into the analyzer tube, where under the influence of the magnetic field, above mentioned, the heterogeneous beam B separates into a plurality of beams B₁, B₂, B₃, each consisting of ions of a given mass-to-charge ratio differing from the mass-to-charge ratio of the ions in the other beams.

A collector system 14, in accordance with the invention includes a barrier 28 which may form the end of the analyzer chamber as shown or which may be spaced therefrom. The barrier has an aperture 28A through which ions are projected from the analyzer tube and forming a first resolving slit. The spectra may be scanned by sweeping the several beams across the aperture 28A either by variation of the propelling potentials in the ion source or by variation of the magnetic field.

A circuit is shown diagrammatically for supplying the necessary potentials to the ion source electrodes and for varying these potentials to scan the ion spectra. This circuit includes a battery or voltage source 30, a slidewire resistor 32 connected across the source and through a tap and switch 34 across a capacitor 35. A second slidewire resistor 36 is connected across the capacitor 35 with one end of this resistor being at the potential of the negative side of the source 30, in this case ground. Pusher electrode 24 is connected toward the positive end of slidewire 36 through a slider 38, the terminal accelerating electrode 26 is connected to the grounded end of the resistor 36 and the first propelling electrode 25 is connected through a slider 40 to an intermediate point on the resistor 36.

To scan the spectrum, switch 34 is closed allowing the capacitor 35 to build up a charge. The switch 34 is then opened and the charge on the capacitor 35 is allowed to discharge across the resistor 36. The potentials between the

several electrodes and the ion source decay with discharge of the capacitor while maintaining relative proportions.

The collector system 14 includes, in addition to the barrier electrode 28, a principal collector electrode 42 substantially surrounded by a grounded shield 44, the electrode 42 and shield 44 being conventional and forming no part of the invention apart from their cooperative relationship with the rest of the collection system. A first auxiliary electrode 46 is mounted adjacent the barrier 28 and has an aperture 46A therein narrower than and in off-center alignment with the aperture 28A in the barrier and forming a second resolving slit. For reasons which will shortly become apparent, the aperture 46A is displaced toward the centers of curvature of the ion beams so that the electrode 46 masks the first resolving slit (aperture 28A) along its edge remote from the centers of curvature. Immediately following the auxiliary electrode 46 in sequential relationship is a second auxiliary electrode 48 having an aperture 48A therein narrower than the aperture 46A in the first auxiliary electrode and oriented so that the electrode 48 masks the second resolving slit (aperture 46A) along its edge proximate to the centers of ion beam curvature. Electrode 48 need not be an apertured electrode as shown and may comprise simply a plate extending inwardly to mask aperture 46A as described, the alignment of the several electrodes being facilitated by such construction. Moreover, both of electrodes 46 and 48 may simply be D shaped members projecting from opposite sides towards the axis of symmetry of the collection chamber. In such event these electrodes may be co-planar or may even be reversed in relative position without in any way affecting the results achieved.

In preferred practice a shield electrode 50 and a metastable suppressor 52 are disposed between the electrode 48 and shield electrode 44. The shield electrode 50 is at ground as is the shield 44, and the metastable suppressor electrode 52 is connected through a tap 54 to a voltage divider 56 connected between taps 58 and 60 of the resistor 36. The potential of the metastable suppressor is thus at a potential intermediate that of pusher electrode 24 and first accelerating electrode 25 of the ion source or, in general, at a potential approximately equal to that maintained in the region of ion formation. If the spectra is scanned by variation of the potentials in the ion source, the potential at the metastable suppressor also varies, thus necessitating the shielding provided by the grounded electrodes 44 and 50 on either side of the metastable suppressor.

The collector electrode 42 is connected through a lead 60 to a first amplifier 66. The two auxiliary electrodes 46 and 48 are connected through a double pole, double throw switch 62 to a network including a lead 63 connected to a second amplifier 68 and a reference potential connection 64 so that when one of said auxiliary electrodes is connected to the second amplifier the other is connected to a reference potential and their positions may be interchanged by simple manipulation of the switch 62.

In preferred practice both the first and second amplifiers are of the negative feed-back type with the main collector electrode 42 being at or very close to ground potential so that the reference potential can be simply ground potential. However, this is not a limitation of the inven-

tion provided only that the auxiliary electrode which is not connected to the second amplifier be connected at a potential substantially equal to that which it would have when used as a collector electrode. In short, the reference potential must closely approximate the potential of the electrodes when connected for amplification.

Assuming that the spectra is scanned by sweeping the ion beams from low mass to high mass as preferred, i. e. from right to left with respect to the first resolving slit 28A, the electrodes 46 and 48 are shown connected for mixture analysis in that the beam B₁ falling on the first auxiliary electrode 46 to the right of the aperture 46A therein and by virtue of its passage through the first resolving slit 28A, is discharged and the discharge signal is amplified in the second amplifier. It should be borne in mind that the beam B₁ following beam B₂ with respect to the assumed direction of beam sweep is composed of ions of higher mass than the beam B₂ and that the beam B₁ will succeed beam B₂ in focus on the collector electrode 42. The resolving power of the instrument with respect to beams B₁ and B₂ when thus connected for mixture analysis is a function of the extent to which electrode 46 masks the first resolving slit together with the resolution afforded by the third resolving slit, the latter being determined by the size of aperture 48A or, in other words, by the unmasked size of aperture 46A. With respect to the center line of the analyzer tube 12, the third resolving slit and the main collector are conveniently centered, while the barrier aperture is displaced off-center toward the centers of curvature of the ion beams. In this fashion resolving power of collector 46 is higher than at collector 48, this being the proper relationship for mixture and isotope ratio analysis, respectively.

If switch 62 is thrown in the opposite direction the second auxiliary electrode 48 will be connected to the second amplifier, so that the signal resulting from discharge of beam B₃ at this electrode will be amplified in the secondary amplifier if the same orientation of ion beams is assumed. Such connection adapts the instrument for isotope ratio measurements. The first auxiliary electrode will, in this case, be connected to reference potential, i. e. grounded in the particular system illustrated. The resolving power of the instrument as between the beams B₂ and B₃ is partially determined by the dimensions of the aperture 46A in the first auxiliary electrode, but principally by the extent to which this aperture is masked by electrode 48. Because of the intended use of the instrument, the resolving power with respect to beam B₃ in isotope ratio measurement is considerably lower than that with respect to beam B₁ in mixture analysis.

Of course in the relatively uncommon situation where the most abundant of several isotopes is that isotope having the highest mass number, the instrument can be connected as though for automatic attenuation for the isotope ratio analysis of such a mixture, providing that the resolving power of an instrument with respect to automatic attenuation is satisfactory for such isotope ratio measurement.

The apparatus of the invention is adapted for use either in isotope ratio measurements or automatic attenuation of mixture analyses without disturbing the collection system of the instrument, by the simple expedient of switching one or the other of two auxiliary collector electrodes to a secondary amplifier and the remaining one

of the auxiliary electrodes to a connection placing it at a potential with respect to ground equal to that of the collector electrode. It is obviously possible to connect each of the auxiliary collector electrodes to separate amplifiers with the two amplifiers being connected respectively to vary the sensitivity of the recording or main amplifier-recording channel and to develop an output ratio with said main amplifier. In such circumstance the switch from mixture analysis to isotope ratio analysis involves simply interconnection of the appropriate auxiliary amplifier in circuit with the main amplifier and connection of the unused collector to reference potential.

As mentioned above, the amplification and comparative circuits employed for this purpose form no part of the invention and may be of the type shown in any of the aforementioned co-pending applications, or may be such a combination of these types as to minimize duplication of circuit elements.

I claim:

1. In a mass spectrometer having an ion source, an analyzer chamber, means for propelling ions from the ion source through the analyzer chamber and means for sorting ions in the analyzer chamber, the combination comprising a barrier electrode and first, second and third collector electrodes arranged in successive spaced relation adjacent the outlet end of the analyzer chamber, the barrier electrode having an aperture therein forming a first resolving slit, the first collector electrode having an aperture therein narrower than and in off-center alignment with the aperture in the barrier electrode and forming a second resolving slit, the second collector electrode being positioned to mask a portion of the aperture in the first collector electrode and forming with the unmasked portion thereof a third effective resolving slit, the third collector electrode being positioned to receive ions passing through the third resolving slit, a first amplifier connected to receive and amplify signals from the third collector electrode, and means for amplifying ion discharge signals at said first and second collector electrodes.

2. In a mass spectrometer having an ion source, an analyzer chamber, means for propelling ions from the ion source through the analyzer chamber and means for sorting ions in the analyzer chamber, the combination comprising a barrier electrode and first, second and third collector electrodes arranged in successive spaced relation adjacent the outlet end of the analyzer chamber, the barrier electrode having an aperture therein forming a first resolving slit, the first collector electrode having an aperture therein narrower than and in off-center alignment with the aperture in the barrier electrode and forming a second resolving slit, the second collector electrode being positioned to mask a portion of the aperture in the first collector electrode and forming with the unmasked portion thereof a third effective resolving slit, the third collector electrode being positioned to receive ions passing through the third resolving slit, a first amplifier connected to receive and amplify signals from the third collector electrode, an auxiliary amplifier and means for interchangeably connecting one of said first and second collector electrodes to said amplifier and the other of said electrodes to a reference potential approximating the potential of the third collector electrode.

3. In a mass spectrometer having an ion source, an analyzer chamber, means for propelling ions

from the ion source through the analyzer chamber and means for sorting ions in the analyzer chamber, the combination comprising a barrier electrode and first, second and third collector electrodes arranged in successive spaced relation adjacent the outlet end of the analyzing chamber, the barrier electrode having an aperture therein forming a first resolving slit, the first collector electrode having an aperture therein narrower than and in off-center alignment with the aperture in the barrier electrode and forming a second resolving slit, the second collector electrode being positioned to mask a portion of the aperture in the first collector electrode and forming with the unmasked portion thereof a third effective resolving slit, the third collector electrode being positioned to receive ions passing through the third resolving slit, a first amplifier connected to receive and amplify signals from the third collector electrode, a shield electrode disposed between the second and third collector electrodes and having an aperture to permit ion access to the third electrode, and means for interchangeably amplifying ion discharge signals at said first and second collector electrodes.

4. In a mass spectrometer having an ion source, an analyzer chamber, means for propelling ions from the ion source through the analyzer chamber and means for causing ions of differing specific mass to follow different curved paths through the analyzer chamber, the combination comprising a barrier electrode and first, second and third collector electrodes arranged in successive spaced relation adjacent the outlet end of the analyzer chamber, the barrier electrode having an aperture therein forming a first resolving slit, the first collector electrode having an aperture therein narrower than and in off-center alignment with the aperture in the barrier electrode and forming a second resolving slit with the first collector electrode masking a portion of the barrier aperture, the second collector electrode being positioned to mask a portion of the aperture in the first collector electrode and forming with the unmasked portion thereof a third effective resolving slit, the third collector electrode being positioned to receive ions passing through the third resolving slit, a first amplifier connected to receive and amplify signals from the third collector electrode, and means for interchangeably amplifying ion discharge signals at said first and second collector electrodes.

5. Apparatus according to claim 4 wherein the masked portion of the aperture in the first collector electrode is larger than the masked portion of the aperture in the barrier electrode.

6. Apparatus according to claim 4 wherein the

aperture in said barrier is off-center toward the centers of ion path curvature with respect to said third effective resolving slit.

7. In a mass spectrometer having an ion source, an analyzer chamber, means for propelling ions from the ion source through the analyzer chamber and means for sorting ions in the analyzer chamber, the combination comprising a barrier electrode and first, second and third collector electrodes arranged in successive spaced relation adjacent the outlet end of the analyzer chamber, the barrier electrode having an aperture therein forming a first resolving slit, the first collector electrode having an aperture therein narrower than and in off-center alignment with the aperture in the barrier electrode and forming a second resolving slit, the second collector electrode being positioned to mask a portion of the aperture in the first collector electrode and forming with the unmasked portion thereof a third effective resolving slit, the third collector electrode being positioned to receive ions passing through the third resolving slit, a first amplifier connected to receive and amplify signals from the third collector electrode, a shield electrode disposed between the second and third collector electrodes and having an aperture to permit ion access to the third electrode, and means for interchangeably amplifying ion discharge signals at said first and second collector electrodes.
8. An ion collector system for a mass spectrometer comprising a barrier electrode and first, second and third collector electrodes arranged in successive spaced relation in the direction of ion travel in the mass spectrometer, the barrier electrode and first collector electrodes having apertures therein of successively decreasing width with the first collector electrode masking a portion of the barrier aperture, the second collector electrode being aligned to mask a portion of the aperture in the first collector electrode, the third collector electrode being aligned with the unmasked portion of the aperture in the first collector electrode and means for amplifying signals produced by ion discharge at the several collector electrodes.
